UNITED STATES PATENT OFFICE.

MILTON RUSLING WOOD, OF EAST ORANGE, NEW JERSEY.

DISPLAY-RACK FOR WINDOWS.

1,096,660.

Specification of Letters Patent.

Patented May 12, 1914.

Application filed May 22, 1913. Serial No. 769,174.

To all whom it may concern:

Be it known that I, MILTON RUSLING Wood, a citizen of the United States, and a resident of East Orange, in the county of 5 Essex and State of New Jersey, have invented a new and Improved Display-Rack for Windows, of which the following is a full, clear, and exact description.

The object of the invention is to provide a 10 new and improved display rack for use in show windows and other places and arranged for convenient attachment to either side of the window casing or other fixed support, and to allow of supporting and displaying various articles of merchandise to the best advantage.

In order to accomplish the desired result use is made of a bracket arranged for attachment to a fixed support and provided 20 with a take-up plate extending at an angle from the face of the bracket, and a supporting arm having its inner end beveled to correspond to the said angle and to abut against the face of the bracket, the said bracket and 25 the beveled end of the said arm having interlocking means for attaching the arm to the bracket and plate to project at an angle from the face of the bracket.

A practical embodiment of the invention 30 is represented in the accompanying drawings forming a part of this specification, in which similar characters of reference indicate corresponding parts in all the views.

Figures 1 and 2 are perspective views of 35 the bracket and the supporting arm in position when assembling the parts; Fig. 3 is a sectional plan view of a show case provided on each side of the casing with a display rack; Fig. 4 is an enlarged face view of the 40 bracket; and Fig. 5 is an enlarged sectional side elevation of the display rack as applied.

The display rack consists essentially of a bracket A and a supporting arm B, of 45 which the bracket A is adapted to be attached to a fixed support C, such, for instance, as the casing side of a show window D, as indicated in Fig. 3. The bracket A is provided with apertures A' engaged by screws E or other fastening devices 50 for attaching the bracket to the fixed support C. The bracket A is provided with a plate or tongue A², preferably struck up from the bracket material and outward, so as to stand at an angle to the face of the 55 bracket. The upper and lower ends of the plate A² are provided with hooks A³, A⁴

having the inner edges of their heads spaced a short distance from the face of the bracket A.

The supporting arm B is preferably tubular and each end B' of the arm is beveled at an angle corresponding approximately to the angle at which the plate or tongue A² projects from the face of the bracket A. The top of the supporting arm B is provided 60 near each beveled end with an opening B² adapted to be engaged with the hook A³ or A⁴ uppermost at the time, and the bottom of the supporting arm B is provided at each beveled end with a slot B³ into which fits the 70 plate or tongue A², the slot D³ being approximately of a length corresponding to the width of the plate or tongue A², so that when the supporting arm B is placed in position on the bracket A and its plate A² then 75 the inner beveled end B' abuts against the face of the bracket A and the uppermost hook locks the supporting arm in position. It is understood that the same bracket A can be used on either side of the 80 window casing D, and it is only necessary to use the bracket with the corresponding hook A³ or A⁴ upward and engaging the corresponding beveled end of the arm B with the 85 corresponding bracket so that both supporting arms B extend at an angle in an outer direction, as will be readily understood by reference to Fig. 3.

In assembling the parts, the operator holds the supporting arm B first in a vertical 90 position, as indicated in Fig. 3, and passes the lower end of the supporting arm over the uppermost hook of the plate A² and engages the hook with the opening B², after which the arm B is swung downward (see 95 Fig. 2) so that the plate A² passes into the slot B³ and the beveled inner end B' finally abuts against the face of the bracket A to fasten the arm in place on the bracket and to support the arm from the bracket at an 100 angle, as previously mentioned and shown in Fig. 3.

The bracket A and the arm B may be made of any suitable material such as metal, 105 cardboard or the like.

Having thus described my invention, I claim as new and desire to secure by Letters Patent:

1. A display rack for show windows and the like comprising a bracket arranged for 110 attachment to a fixed support and provided with a plate extending at an angle from the

face of the bracket, and a supporting arm having its inner end beveled to correspond to the angle of said plate and to abut against the face of the bracket, the said bracket and 5 beveled end of the said arm having interlocking means for attaching the arm to the bracket and plate to hold said arm projecting at an angle from the face of the bracket.

2. A display rack for show windows and 10 the like, comprising a flat bracket provided with a struck-up plate extending vertically and at an angle to the face of the bracket, the upper and lower ends of the plate being provided with hooks, the inner edges of 15 which are spaced from the face of the plate, and a supporting arm having a beveled inner end and provided with an opening at the top near the beveled end for engagement by either of the said hooks, the said arm being provided at the beveled end with a slot in 20 register with the opening, the opening being engaged by the said plate.

3. A display rack for show windows and 25 the like, comprising a bracket adapted to be fastened to a fixed support and having a struck-up plate extending at an angle to

the face of the bracket and provided at its upper end with a hook, and a tubular supporting arm having a beveled end face and provided at the top near the said beveled end 30 with an opening engaged by the said hook, the said arm being provided at its bottom with a slot disposed opposite the said opening and engaged by the plate.

4. A display rack for show windows and 35 the like, comprising a bracket provided with a struck-up plate extending at an angle to the face of the bracket, the plate being provided at both ends with hooks, and a tubular supporting arm having beveled ends each 40 provided with an opening and a slot in register with the opening, the opening being engaged by one of the hooks and the slot being engaged by the plate.

In testimony whereof I have signed my 45 name to this specification in the presence of two subscribing witnesses.

MILTON RUSLING WOOD.
